UNITED STATES PATENT OFFICE.

CLARENCE J. BRUCKLE, OF ST. PAUL, MINNESOTA, ASSIGNOR OF ONE-FOURTH TO ROY H. CURRIE, OF ST. PAUL, MINNESOTA.

REENFORCED BOTTLE CASE.

Application filed April 6, 1925. Serial No. 20,938.

My invention relates to reenforced bottle cases and particularly to bottle cases which are provided with a plurality of compartments for receiving and holding bottles such as milk and cream bottles in upright position. The cases are used for shipping and delivering the bottles and are intended for repeated use. While being handled, the cases are subjected to a great deal of rough usage so that it is desirable that they be strong and durable. An object therefore of my invention is to provide a case of novel construction which makes it very strong and durable, easy of repair and economical in manufacture.

The full objects and advantages of my invention will appear in connection with the detailed description thereof and the novel features in my inventive idea will be particularly pointed out in the claims.

In the accompanying drawings which illustrate two forms in which my invention may be embodied, Fig. 1 is a top plan view of one form of the invention. Fig. 2 is a side view thereof. Fig. 3 is a view in vertical section on the line 3—3 of Fig. 1. Fig. 4 is an end view. Fig. 5 is a fragmentary view in horizontal section on the line 5—5 of Fig. 3. Fig. 6 is a fragmentary view in vertical section on the line 6—6 of Fig. 3. Fig. 7 is a fragmentary view in vertical section on the line 7—7 of Fig. 1. Fig. 8 is a plan view of a sheet metal supporting member. Fig. 9 is a top plan view of another form of the invention. Fig. 10 is a side view thereof. Fig. 11 is a fragmentary view in vertical section on the line 11—11 of Fig. 9.

In the drawings, Figs. 1 to 8 show a form of the invention intended particularly for cream bottles and Figs. 9, 10, and 11, show a form intended particularly for milk bottles. Altho many of the features of construction are the same for both forms, the cases for cream bottles do not need to be as high as those for milk bottles and while the length and breadth of the two forms are preferably the same, in order that they may be readily stacked together, it is obvious that the cases for cream bottles will have a greater number of compartments than the cases for milk bottles. I have shown the cases for cream bottles provided with 20 compartments, while the cases for milk bottles are provided with 12 compartments.

Referring first to the form shown in Figs. 1 to 8, I show a wooden, rectangular box-like structure, each of whose sides consists of an upper slat 10 and a lower slat 12 while each of its ends consists of an upper slat 14 and a lower slat 16. The two lower slats 12 are protected at the bottom by angle strips 18 of metal while the two lower slats 16 are protected at the bottom by angle strips 20 of metal. The horizontal flanges of these angle strips extend under the lower edges of the slats, while the vertical flanges of the angle strips extend part way up the outer surfaces of the slats as is apparent from Figs. 3 and 4. The flanges referred to as vertical are not strictly vertical but are inclined inwardly as shown in Figs. 6 and 7, the slats being cut away to permit this inclination with the result that the upper edges of the flanges are inset to provide a smooth joint. The upper slats 10 and 14 are spaced from the lower slats 12 and 16 respectively, blocks 22 being interposed at the corners and the corners are reenforced on the outside by metal angle strips 24 each of whose edges is provided with two inclined cuts to provide ears 25 which are bent inwardly and then upwardly around the bottom edges of the upper slats and blocks 22 respectively as will clearly appear from Figs. 5 and 6 whereby horizontal flanges 26 are produced which support the upper slats and the blocks. The angle strips 24 are miter-cut at the top and bent over and downwardly around the upper edges of the slats as indicated at 28 in Fig. 1. The lower ends of the angle strips 24 extend down over the flanges on the strips 20 as will be seen in Figs. 5 and 6. The corners are reenforced on the inside by metal angle strips 30 secured by rivets 32 which extend through these strips and through the slats and outside strips 24 and also through additional metal corner pieces 34 at the bottom which are bent around the bottom of the case so as to have flanges 36 lying under strips 30. The upper ends of the strips 30 extend above the case and are offset inwardly to provide projections 38 so that the cases may be held in stacked position one on another. As will be apparent from Fig. 1, three longitudinal partition bars are provided, there being two of these bars designated 40 located toward the sides of the case and between which is

an intermediate bar 42. These partition bars are located toward the bottom of the case and the two bars 40 are secured by means of sheet metal pieces 44 which are 5 cut to the shape shown in Fig. 8 and have an upper ear 46, a lower ear 48, and two slide wings 50 which at their top are cut loose from the middle portion so that they can be bent on lines 52. The ear 46 of each 10 piece 44 contains a hole, there being a rivet which passes through this hole and through the upper slat 14 for attachment of the pieces 44. The bars 40 are secured at their ends by bending the wings at right 15 angles on the lines 52 and on lines 54 while the ear 48 is bent up on the line 56 as will be understood from Figs. 1 and 3. By bending the pieces 44 around the ends of the bars in this manner, the latter will be 20 firmly supported in place. The cross-wise partitions are formed by four pairs of rods 56 which pass through the bars 40 and through the intermediate bar 42 thereby supporting the latter bar which at its ends is 25 beveled as indicated at 58, in order that the upper slats may be readily grasped underneath. The bottom support for the bottles is constituted by a plurality of longitudinal rods 60 whose ends pass through the bottom 30 end slats, these rods being supported intermediately by two angle bars 62 whose ends are riveted to the bottom end slats 16.

The case shown in Figs. 9, 10 and 11 is reenforced in a manner similar to that 35 already described and so far as applicable the same reference characters are used. The case shown in these last three figures is intended for larger bottles and is higher and provided with fewer partitions than 40 the other form. Referring to Fig. 10 which shows a side view similar to Fig. 2, it will be noted that in addition to the top slat 10 and bottom slat 12 there are two slats 64 and 66 placed above the bottom slat 12 45 with a space provided between the top slat 10 and the slat 66 by means of corner blocks 22. It will be understood that each end of the case is similarly provided with additional slats and that the vertical corner reinforcing strips are longer than in the form 50 first described. The interior construction is considerably modified to provide fewer compartments. As shown, there are two pairs of longitudinal rods 68 and three pairs of 55 cross rods 70 which extend through the additional slats 64 and 66. The supporting bottom for the milk bottles is formed by longitudinal rods 60, the number of which is less than that for the other form; an 60 angle bar 72 extends centrally of the case between the bottom slats 12. Two vertical angle bars 74 are supported at their bot-

toms by the bar 72. As will be apparent from Fig. 9, the pairs of rods 68 pass through holes in the vertical angle bars 74 65 and the middle rod 70 passes through holes in the bars 74 so that the longitudinal and cross rods are effectively supported at intermediate positions.

I claim:—

1. A reenforced bottle case comprising upper and lower end slats, upper and lower side slats, metal angle strips extending under the lower edges and part way up the outside of the lowermost slats, metal angle strips secured on the outside of the corners of the case, said strips having inclined cuts to provide ears which are bent inwardly under the bottom edges and then upwardly into engagement with the inner surfaces of the upper slats, said last mentioned strips extending over the upturned portions of said first mentioned strips, metal angle strips secured at the bottom corners of the case over the lower ends of said second mentioned angle strips, flanges on said bottom strips extending under the lowermost slats and then upwardly into engagement with the inner surfaces thereof, and metal angle strips secured on the inside of the corners of the case, said last mentioned strips being positioned over the upturned portions of said flanges and of said ears for securing the same in place.

2. A reenforced bottle case comprising upper and lower end slats, upper and lower side slats, metal angle strips extending under the lower edges and part way up the outside of the lowermost slats, the upwardly extending portions of said strips being inset 95 to make a smooth joint with the slats, metal angle strips secured on the outside of the corners of the case, said strips having inclined cuts to provide ears which are bent inwardly under the bottom edges and then 100 upwardly into engagement with the inner surfaces of the upper slats, said last mentioned strips extending over the upturned portions of said first mentioned strips, metal angle strips secured at the bottom corners 105 of the case over the lower ends of said second mentioned angle strips, flanges on said bottom strips extending under the lowermost slats and then upwardly into engagement with the inner surfaces thereof, and metal angle strips secured on the inside of the corners 110 of the case, said last mentioned strips being positioned over the upturned portions of said flanges and of said ears for securing the same in place.

In testimony whereof I hereunto affix my signature.

CLARENCE J. MUCKLE.
